UNITED STATES PATENT OFFICE.

WALTER A. TRATSCH, OF CHICAGO, ILLINOIS.

AMUSEMENT DEVICE.

Application filed March 14, 1927. Serial No. 175,184.

This invention relates to amusement devices and more particularly to coin controlled mechanisms involving a target toward which balls may be fired, and has for 5 its object to provide a construction, simple in operation and more efficient in use than those heretofore proposed.

With these and other objects in view the invention consists in the novel details of construction and arrangements of parts as will be more fully hereinafter disclosed and particularly pointed out in the claims.

Referring to the accompanying drawings forming a part of this specification in which like numerals designate like parts in all the views;

Fig. 1 is a vertical sectional view taken longitudinally through an amusement device provided with this invention;

20 Fig. 2 is a perspective view of a detail of the actuating rod employed to set the targets as well as to actuate a register or counting mechanism;

Fig. 3 is a rear elevational view, partly 25 in section, of the target construction forming the subject matter of this invention;

Fig. 4 is a partial horizontal sectional view illustrating the slide adapted to release marksmanship medals used in connection with this invention;

Fig. 5 is a horizontal sectional view similar to Fig. 4 with the parts in a different position;

Fig. 6 is a vertical sectional view taken as 35 on the line 6—6 of Fig. 4 and looking in the direction of the arrows;

Fig. 7 is a vertical sectional view taken as on the line 7—7 of Fig. 5 and looking in the direction of the arrows;

40 Fig. 8 is a partial rear elevational view, partly in section, of some of the targets involved in this invention;

Fig. 9 is a perspective detail view of the slide employed in connection with the discharge of marksmanship medals, illustrated 45 in Figs. 4 to 8 inclusive;

Fig. 10 is a front elevational view of the targets toward which the balls may be fired;

Fig. 11 is a vertical sectional view through 50 a target taken as on the line 11—11 of Fig. 3 and looking in the direction of the arrows;

Fig. 12 is a view similar to Fig. 11 but taken as on the line 12—12 of Fig. 3 and showing the target in a different position;

Fig. 13 is a horizontal detail sectional view taken as on the line 13—13 of Fig. 11 and looking in the direction of the arrows; and

Fig. 14 is a detail vertical sectional view of one of the target flags illustrated in Figs. 60 11 and 12 in a different position from that shown in said figures.

In order that this invention may be the better understood it is said that there was issued to Walter A. Tratsch the United 65 States Patent #1,551,858, dated September 1, 1925, and entitled "Amusement device" in which there was disclosed a miniature shooting gallery provided with a target generally indicated by the numeral 3, and a pistol generally indicated by the numeral 10 forming the subject matter of said patent.

The pistol disclosed in said patent was provided with a coin receiving slot, an operating slide adapted to force a coin of requisite 70 size past a locking lever whereby the actuating parts of the pistol would be placed in operative position so that balls could be successively fired from the pistol toward said target. The pistol was universally mounted by the provision of suitable pivots to provide for vertical and horizontal movement of said pistol to cover the range of the target.

With particular reference to Figs. 75 3 and 7 of said patent and the specification 80 thereof it will be observed that the actuating slide 70 of said pistol is provided with a pin 81 rigid therewith connected to one end of a lever 82 adapted to actuate, on the full stroke thereof, the counting mechanism 85 generally indicated by the numeral 83.

In the amusement device now to be disclosed there is provided a pistol 10 substantially a duplicate in all its parts of the pistol disclosed in said patent and mounted just as was the patented pistol in a cabinet 1 of substantially the same general construction as the cabinet disclosed in said patent. However, the actuating lever 82 used in connection with this invention and 90 corresponding to the similar actuating lever of said patent does not directly operate the counting mechanism, but one end 88 thereof does extend out of said pistol just as did the corresponding end of the same lever disclosed in said patent. Stated in still 95 other language, the cabinet inclosing the invention forming the subject matter of this 100

application is provided with the glass top 2, the inclined floor 4 provided with the groove 5 adapted to return the fire balls 6 to the pistol 10 just the same as the parts 5 bearing the same numerals in said patent.

The cabinet 1 is provided with a false bottom 7 immediately below the end of the actuating lever 82 and to this false bottom is secured a suitable guide bracket 8 through 10 which passes an actuating rod 12 having secured thereto at the pistol end a casting 13 provided with a concave spherical surface 14 with which the end 88 of the actuating lever 82 of the pistol 10 coacts. In other 15 words, the pistol 10, as hereinbefore stated, is mounted exactly as was the pistol of the patent referred to, for both a vertical and a horizontal movement, and therefore the spherical surface 14 is provided so that the 20 end 88 of the pistol actuating lever 82 may bear the same relation to the actuating rod 12 no matter what position the pistol 10 assumes. Thus it will be seen that when the actuating slide, (not shown in the drawings, but with which the pistol is provided) 25 is actuated, the lever 82 will be moved forwardly and the end 88 thereof, bearing against the surface 14 of the casting 13, will move the latter likewise forwardly or away 30 from the pistol.

The other end of the actuating rod 12 is provided with a vertical plate 16 adapted to move in a slot 17 of a guide bracket 18 secured to the cabinet in any suitable manner. The upper and extreme end portion of the plate 16 is provided with a bevel surface 19 for a purpose presently to be disclosed, and said plate is further provided with a diagonal slot 20 adapted to receive a pin 21 35 carried by the crank 22 adapted to actuate the counter mechanism generally indicated by the numeral 25 and of any well known type. With particular reference to Fig. 1 it will thus be seen that when the actuating lever 82 of the pistol is moved forwardly, the actuating rod 12 will likewise be moved forwardly or to the left as seen in said figure whereupon the plate 16 will be so moved in the slot 17 of the bracket 18 that the diagonal slot 20 provided in said plate will cause the pin 21 to move upwardly and partially turn the crank 22 to actuate the counting device 25. Stated in other words, each time a coin is inserted in the pistol 10 and the 40 actuating slide moved to set the parts of the pistol in operative position the counting mechanism 25 will be actuated to register the coin just inserted in the pistol all as will be readily understood. To insure the return 45 of the actuating rod 12 there is provided a helical spring 26 one end of which is secured to the guide bracket 8 and the other end of which is fastened to the plate 16 to pull the latter backwardly or to the right 50 as seen in Fig. 1 when permitted to do so by

the position of the actuating lever 82 of the pistol 10.

The guide bracket 18, in the exemplification of this invention illustrated in the drawings, is secured to and depends from plate 70 30 provided with a plurality of apertures 31, one for each target of which there may be as many as desired, five being shown in the drawings. Above each target aperture 31 is an aperture 32 through which may be 75 seen, by the operator of the device, any suitable indicator or flag 33 which is adapted to drop into registry with its particular aperture 32 when the target therebelow has been hit by a fired ball. There will of course 80 be as many apertures 32 as there are apertures 31 and there will be as many flags 33 as there are indicator apertures 32. In this connection it might further be stated that each flag 33 will be of a different and distinguishing color to make the amusement device more attractive. The target plate 30 is rigidly secured, as by the screws 34, to the cabinet 1 and is positioned in substantially a vertical plane so that the balls fired 90 may strike as perpendicularly as possible the targets behind the plate 30.

With particular reference to Fig. 3 it will be seen that to the lowermost edge portion of the plate 30 and on the rear side thereof there is secured as at 36 a bar 37 to which is secured the plurality of targets. That is to say, to this bar there is secured in spaced relation as at 38 one end of a flat spring member 39 to which is secured as at 40 a target 41 so that said target is concentrically disposed with reference to its aperture 31 in the plate 30, the target 41 being of substantially the same thickness as the bar 37 adapted to support the same. Each target 41 is secured at about the mid-point of its spring member 39, and to the free end of each spring member there is secured a pin 42 adapted to extend therefrom toward the plate 30. The purpose of each pin 42 is to contact with the bottom edge portion 43 of a coacting member 44 adapted to slide between a pair of guides 46 provided therefor as clearly shown in Fig. 3, said guides being secured as by the rivets 47 to the plate 100 30. Each member 44 carries an aforementioned indicator or flag, on the face thereof contacting with the plate 30, and which may comprise a circular recess provided with a coloration indicated by the numeral 50, said coloration being of paint, enamel, or any other suitable substance. When a member 44 is in its uppermost raised position as seen in Fig. 11, the lowermost edge 43 thereof will be supported by the pin 42 of its associated target spring member 39, but when one of the targets such as 52, see Figs. 3 and 110 12, has been struck by a ball fired from the pistol 10, the force of the impact will 120 be great enough to deflect the target spring 125 130

member 39 rearwardly so that the pin 42 carried thereby will be moved a sufficient distance, for the moment, to permit the flag slide member 44 cooperating therewith 5 to drop in its guides, this movement being augmented by a coil spring 54 interposed between a post 55 carried by and disposed near the upper extremity of the flag member 44, and a post 56 passing through the target 10 spring 39 and supported by the cross bar 37 and its supporting plate 30, see Fig. 12. Thus it will be observed that the spring member 39 is prevented from a turning movement about its rivet 36 by the post 56. 15 The downward movement of a flag slide 44 is stopped when the pin 55 carried by said member comes in contact with the upper edge portion of a cross bar 58 supported as at 59 to the outermost guides 46 for the flag 20 members 44, see Fig. 14. When said post 55 is in contact with said bar 58, the colored flag 33 associated therewith, will be in full and concentric registration with the particular aperture 32 provided therefor, as 25 clearly indicated in said figure.

It is to be observed from the figures of the drawings that the target apertures 31 are of varying sizes, the largest exposing a target surface, which would be easier to hit 30 with a fired ball, than the target surface exposed by the smaller of the target apertures, see Fig. 10. Thus by this invention there is provided what may be said to be a gradation of targets, the smallest of which would 35 require much more skill to strike than would a larger target. In this connection, however, it is to be understood that all of the targets 41 are of the same size, but by having the apertures 31 in front of each target 40 of diminishing sizes, the effect is had of providing targets of different sizes. The targets, if desired, could be made of metal of various thicknesses and so mounted as to cause a distinct "ring" or sound when struck 45 by a fired ball, but for clearness in the drawings they have all been shown as disks of the same shape and dimensions.

This improved target is automatically set before the pistol 10 can be operated for firing 50 balls, said setting being accomplished in the following manner. There is provided a T-bar comprising the vertical portion 60 at the upper extremity of which is rigidly secured the head 61, the vertical portion 55 being provided with two slots 62 and 63 each to receive in sliding engagement therewith a pin carried by the spacing posts 64 and 65 supported by a guide 46 and the cross bar 37 respectively. The T-bar is held 60 in any suitable manner on the pins, such as by the provision of washers 66 maintained in place as by cotter pins 67, see Fig. 3. The parts are so dimensioned that the T-bar 60 is free to slide in a vertical direction within 65 the limits governed by the slots 62 and 63.

The lower extremity 68 of the T-bar is adapted to contact with the inclined surface 19 of the plate 16 of the actuating rod 12 when the latter is moved by the lever 82 of the pistol 10. That is to say, to operate the pistol, a coin of the proper size must be inserted in the slot provided therefor and the coin actuating slide properly moved (all in accordance with the disclosure in said Patent #1,551,858) whereupon the lever 82 will 70 be moved. This will in turn correspondingly move the actuating rod 12 whereupon the inclined edge 19 of the plate 16 associated therewith will have a camming effect with relation to the T-bar causing the same to 75 be moved upwardly. When this occurs, the head of the T-bar formed by the cross member 61 will come in contact with the pins 55 of each of the target flags 33 that are in lowered or visible position, and raise the 80 members 44 associated therewith through such a distance as will permit the pin 42 carried by the cooperating target spring member 39 to slip into place under the lowermost edge 43 of said flag members 44. 85 The slots 62 and 63 in the T-bar are of sufficient length to permit the desired vertical movement to "set" the target. After this is accomplished, the actuating rod 12 is returned to its normal position as shown in 90 Fig. 1 by action of the spring 26 and the associated parts of the pistol. The pistol is then ready for firing, and all of the flags will be raised so that the colorations 50 will 95 be out of sight, ready to be dropped into 100 view when the targets 41 associated therewith are struck by the fired balls.

With particular reference to Figs. 3, 8, 11, 12 and 14 it will be observed that there is a second T-bar provided in the rear of the targets comprising the vertical member 70 and a cross bar 71 rigidly secured to the upper end thereof. The vertical member 70 is provided with spaced slots 72 and 73 adapted to slidably engage the pins 74 and 75 carried by spacing posts such as 76 (see Fig. 12) whereby the vertical member 70 is maintained in parallel relation with the target plate 30 in such manner that the operation thereof will not interfere with the cross bars 37 and 58 and the member 61 of the other T-bar 60. Any suitable means such as the cotter pins 77 may be employed to hold the member 70 against the shoulder formed by the spacing posts 76 all as will be readily understood. The head 71 is provided with a plurality of elongated apertures such as 80 in registry with and slidably cooperating with the upper posts 55 of any desired number of target flags. That is to say, the head member 71 is shown in Fig. 3 as being of sufficient length to coact with the upper pins 55 associated with three of the flags which in turn are associated with the targets, but it is to be understood that said 115 120 125 130

head member 71 may be of any desired length to coact with a greater or lesser number of these flags.

Each elongated opening 80 in the cross head 71 will prevent the flag slide 44 associated therewith from moving downwardly in its guides a distance sufficient to disclose the entire coloration 50 of the flag through an opening 32 in the target plate 30 thereby making it possible to have indications of struck targets which are variable. In other words, when the target 41 is struck there will be a full indication thereof whereas when either of targets 84, 85 or 86 are struck there will be only a partial indication, and when all of said last mentioned targets are struck the partial indications thereof will be changed to full indications. That is to say, it is highly desirable to indicate when a target has been struck but it is more highly desirable to make the obtaining of a medal difficult. Therefore the variable indications are provided to make known those targets which have been struck and yet control the dispensation of a medal in accordance with a predetermined handicap. In the drawings, Figs. 3 and 10 show a disposition of parts whereby the cross head 71 is adapted to control the flags of the targets just mentioned, two of said flags having been partially lowered into view as indicated by the numerals 81 and 82 while the third still remains in its uppermost position as indicated at 83. This is an indication that the operator of the device has been successful in striking the particular targets such as 84 and 85 with the fired balls. If the operator of the device is further successful in striking the target indicated by the numeral 86 associated with the flag 83 which is controlled by the cross head 71, then this amusement device is adapted to discharge a marksmanship medal. Stated in still other words, and as before stated, the larger of the targets are more easily hit by fired balls than are the smaller targets and therefore this device is intended to reward the skill of the operator thereof should he be fortunate enough to hit a predetermined number of the smaller targets.

Since the mechanism for dispensing the marksmanship medals, presently to be described, is only operated when the T-bar 70 moves downwardly, it will be obvious that a medal will not be discharged so long as one of the pins 55 associated with the T-bar 70 is in its uppermost position. That is to say, the T-bar 70 is supported by these pins 55 which are rigid with the slidable members 44 carrying the flags 33 and which are adapted to be retained in their uppermost positions by the pin 42 on each target spring member 39 upon which said members 44 are adapted to normally rest, see Fig. 11. Upon the striking of targets associated with those

pins 55 which support the T-bar 70, the pin 55 of each struck target will move downwardly in its elongated aperture 80 in the cross head 71 due to the action of gravity plus the action of a spring 54, but not through a distance sufficient to permit the dropped pin 55 from resting on the cross bar 58 which is adapted to limit the lowermost position that said pin can assume and as heretofore described. Consequently all of the targets associated with the pins 55 supporting the T-bar 70 must be struck to permit the downward movement of said T-bar, and the discharge of a medal. When this occurs all of the dropped pins come in resting contact with the upper edge of the cross bar 58.

The mechanism for dispensing a reward token, such as a marksmanship medal, comprises a magazine 90 for a vertical stack of said medals the lower end of which has associated therewith a slide 91 provided with an aperture 92 of sufficient size to permit the reception of one of said medals such as indicated by the numeral 93, see Figs. 6, 7 and 9. The slide 91 is of substantially the same thickness as a medal and the aperture 92 thereof is so disposed in said slide that there will be provided an imperforate portion 94 adapted at times to be disposed beneath the stack of medals in the magazine 90. That is to say, when the slide is intermittently actuated, as presently to be disclosed, it is first in the position shown in Fig. 6 with the aperture 92 in concentric relation with the stack of medals. In this disposition of parts the lowermost of the medals will lie in said aperture 92, it being of course understood that the slide 91 has therebeneath a suitable support 95, secured to the cabinet 1, having an imperforate portion 96 immediately below the magazine 90 and a perforation or opening 97 adjacent the imperforate portion through which a medal may fall. Upon the next actuation of the slide 91, the same will be moved toward the right as seen in Figs. 6 and 7, assuming the position shown in the latter figure, whereupon the medal lying in the aperture 92 of said slide will be moved in a horizontal plane out of the vertical pile of medals and over the opening 97 in the bracket 95 through which it will fall into a trough 98 leading to a delivery cup 99 outside the cabinet 1 and from which said medal may be obtained by the operator of the device. Upon the next actuation of the slide in the opposite direction, the aperture 92 thereof will be made to assume a position under the magazine 90 so that the lowermost of the medals therein will drop into said aperture for subsequent movement to the discharge trough 98.

The slide 91 is provided with an upturned portion or lug 100 constituting a stop for the slide when it comes in contact with the base of the magazine 90 and which is so posi-

tioned as to insure the registry of the aperture 92 of said slide with the medals in said magazine. One side edge portion of the slide is extended as at 101 and has its end 5 upturned or otherwise provided with a post 102 adapted to receive one end of a coil spring 103, the other end of which is suitably secured to the cabinet 1 in any suitable manner as by the employment of a post 104, 10 said spring adapted to move the slide 91 in its guides 105 to bring a medal into position for discharge into the trough 98. The other side portion of the slide 91 is also extended as at 107 and is provided in the extreme 15 outer end portion thereof with a notch 108 adapted to coact with the toe 109 of a locking bar 110 provided with slots 111 and 112 slidably engaging pins 113 and 114 respectively, rigidly secured to the bracket 95. 20 Near the end of the bar 110 opposite the toe 109 and in one lateral edge thereof there is provided an opening 115 adapted to receive the lowermost end of the vertical member of the T-bar 70. This end portion of the T-bar, 25 as clearly illustrated in Figs. 3 and 8, is reduced in width and is so deformed as to provide a cam 120. When the T-bar 70 is moved into its raised position, as shown in Figs. 3 and 4, the cam 120 thereof will force the 30 slidable locking bar 110 toward the medal slide 91 and the toe 109 of said locking bar will engage the notch 108 of said slide, thereby preventing the spring 103 from moving said slide to dispense a medal. 35 When the T-bar is moved into its lowered position, as shown in Figs. 5 and 8, the cam 120 will cause a movement of the locking bar 110 away from the medal discharging slide 91, thus withdrawing the toe 109 from the 40 notch 108 and permitting the spring 103 to move the slide 91 to discharge its medal, a stop pin 124 in the bracket 95 being provided for limiting the movement of the slide 91 in this direction. 45 As previously described the targets are reset when the actuating rod 12 is moved in a direction away from the pistol 10 after the insertion of each coin to unlock the pistol mechanism, said setting of the targets being 50 accomplished by the cam surface 19 contacting with and causing the upward movement of the T-bar 60. When the actuating rod 12 moves to accomplish this result, the free end of the plate 16 associated with said rod 12 55 comes in contact with the upturned lug 100 of the medal slide 91 and in the continued movement of said plate 16 causes the slide 91 to move in under the medal magazine 90 to cause the aperture 92 in said slide to receive the lowermost medal in said magazine. 60 When this movement of the slide 91 is completed, the notch 108 associated therewith will be in position to receive the toe 109 of the locking lever 110. When the cam surface 19 associated with the actuating rod 12

moves the T-bar 60 upwardly, all the pins 55 associated with the flag members 44 which are in down position will be moved upwardly due to their contacting position with the cross head 61 of said T-bar 60. 70

If, for the previously inserted coin, the special targets or those such as indicated in Figs. 10 by the numerals 84, 85 and 86 have not been hit and therefore caused a medal to be dispensed from the device, then the slide 75 member 91 will have remained in the position shown in Fig. 4 or in other words, it will have remained locked as by the bar 110. On the other hand, if a medal has been dispensed, 80 then the targets 84, 85 and 86 will have been struck and the flags 81, 82 and 83 will all be in down position and fully visible, and also the pins 55 associated therewith will likewise be down and in supporting contact with the upper edge portion of the cross bar 58. 85 In this latter case upon the upward movement of the T-bar 60 by the actuating rod 12, all of the pins of the special targets (controlling the dispensing of the medals) being 90 down, will be moved upwardly when the cross head 61 of said T-bar 60 comes in contact with said pins.

In this movement said pins 55 will travel the length of the elongated slots 80 in the cross head 71 of the T-bar 70 without producing any action upon said T-bar, but said slots are of such a short length as to cause the T-bar 70 to be raised upon the continued upward movement of said pins 55. This results, of course, in the moving of the cam 100 120 carried at the lower extremity of the T-bar 70 with a consequent sliding movement of the locking bar 110 from its position shown in Fig. 5 to its position shown in Fig. 4. While the locking bar 110 is thus 105 moving, the medal dispensing slide 91 is being moved in a direction toward the magazine 90, and the parts are so dimensioned that the toe 109 of the locking bar 110 will enter the notch 108 of the slide 91 when said 110 notch reaches a position in the line of travel of said locking bar. This locking of the slide 91 is automatically accomplished, it will be seen, by the movement of the plate 16.

The simplicity of construction and the 115 possible interchangeability of parts is to be noted. In other words, a device of this character might be installed in a locality where it would be used by persons not having a high degree of skill in target shooting with a pistol with the result that it would be highly difficult for them to hit the targets controlling the dispensing of medals or trade tokens. If this were the case it might be desirable to reduce the handicap placed on 120 the persons operating the device, or in other words, it would be desirable to diminish the degree of skill required in the obtaining of the marksmanship medal or token. In the drawings illustrating this device, the three 125 130

smallest targets have been shown associated with the medal releasing mechanism thus requiring the hitting of all three small targets to actuate the same, which is a condition requiring relatively great skill. To reduce the amount of skill required to obtain a marksmanship medal, therefore, it is only necessary to remove the T-bar 70 and to replace it with another T-bar having a cross head 75 adapted, for instance, to coat with but two of the smaller targets. Or, if occasion necessitates, a T-bar coacting with but one of the smaller targets may be substituted; and still again a T-bar may be provided for coacting relationship with only the larger of the targets. In fact T-bars will be made to be substituted as occasion demands for the one shown in Fig. 3 adapted to coat with any and all combinations of targets. No 20 matter, however, which T-bar will be used, each will be capable of substitution for the one illustrated in Fig. 3 and the lower end of each T-bar will be made exactly similar to the construction of that shown in the 25 drawings so that each T-bar will coat with the locking bar 110 without the necessity of providing a different locking bar or a vertical member with a different cam. Further it is to be observed that all of the targets 30 are of the same size and therefore are interchangeable, and that all of the flag members 44 are of the same size thus making for interchangeability as well as cheapness of production. All of the springs 54 are of the 35 same size and here again is incorporated a feature greatly reducing the cost of manufacture. The several bars and other structural elements may be made from sheet material of the same thickness and this additionally reduces the cost of production in 40 that the parts can be readily stamped from said material by suitable machinery.

From the foregoing disclosure it will thus readily be seen that by this improved construction there is provided a coin controlled 45 means for successively firing a predetermined number of balls which is the pistol 10, in combination with a plurality of targets 41 toward which said balls may be fired. Further means comprising the flags 33 are 50 provided for visibly indicating, through the apertures 32, the targets hit by said fired balls, as well as common means comprising the actuating rod 12, the cam 19 associated 55 therewith, coacting with the pistol 10, all for simultaneously setting the targets, actuating a coin counting mechanism, and actuating the means for dispensing a marksmanship medal.

It is obvious that those skilled in the art 60 may vary the details of construction as well as the combinations of parts within the scope of this invention without departing from the spirit thereof, therefore it is not 65 desired to be limited to the foregoing dis-

closure except as may be required by the claims.

What is claimed is:

1. In an amusement device of the character described the combination of means for successively firing a predetermined number of balls; a plurality of targets toward which said balls may be fired; and slidable means for visibly indicating the targets hit by said balls. 75

2. In an amusement device of the character described the combination of means for successively firing a predetermined number of balls; a plurality of targets toward which said balls may be fired; and slidable means supported by said target for visibly indicating the targets hit by said balls. 80

3. In an amusement device of the character described the combination of means for successively firing a predetermined number of balls; a plurality of targets toward which said balls may be fired; and vertically slid- 85 able means for visibly indicating the targets hit by said balls; said means normally supported by said targets but adapted to drop 90 under the action of gravity when said targets are moved from thereunder upon being hit.

4. In an amusement device of the character described the combination of means for successively firing a predetermined number of balls; a plurality of targets toward which said balls may be fired; slidable means for visibly indicating the targets hit by said balls; and slidable means actuated by said 95 indicating means to dispense a medal when certain of said targets are struck.

5. In an amusement device of the character described the combination of means for successively firing a predetermined number of balls; a plurality of targets toward which said balls may be fired; slidable spring tensioned means provided with a pin for visibly indicating the targets hit by said balls; slid- 105 able means actuated by said pins to dispense 110 a medal when certain of said targets are struck; and common means for setting said targets and dispensing means.

6. In an amusement device of the character described the combination of means for successively firing a predetermined number of balls; a plurality of targets toward which said balls may be fired; slidable means for visibly indicating the targets hit by said balls; and common reciprocating means co- 115 acting with said first named means for simultaneously setting said targets and said indicating means. 120

7. In an amusement device of the character described the combination of means for successively firing a predetermined number of balls; a plurality of targets toward which said balls may be fired; slidable means provided with a pin for visibly indicating the targets hit by said balls; slidable spring con- 125

trolled means actuated by said pins to dispense a medal when certain of said targets are struck; and common means for simultaneously setting said targets, said indicating means, said dispensing means, and actuating a counting mechanism.

8. In an amusement device of the character described the combination of means for successively firing a predetermined number of balls; a plurality of targets toward which said balls may be fired; slideable means for visibly indicating the targets hit by said balls; and means for dispensing a medal when certain of said targets are struck.

15 9. In an amusement device of the character described the combination of means for successively firing a predetermined number of balls; a plurality of targets toward which said balls may be fired; slideable means supported by said targets in the plane thereof for visibly indicating the targets hit by said balls; and means for dispensing a medal when certain of said targets are struck.

10 10. In an amusement device of the character described the combination of means for successively firing a predetermined number of balls; a plurality of targets toward which said balls may be fired; slideable means one for each target and normally supported thereby for visibly indicating the targets hit by said balls; and means for dispensing a medal when certain of said targets are struck.

15 11. In an amusement device of the character described the combination of means for successively firing a predetermined number of balls; a plurality of targets toward which said balls may be fired; slideable means for visibly indicating the targets hit by said balls; and means actuated by said indicating means for dispensing a medal when certain of said targets are struck.

16 12. In an amusement device of the character described the combination of means for successively firing a predetermined number of balls; a plurality of targets toward which said balls may be fired; slideable means for visibly indicating the targets hit by said balls; and means including a cam actuated by said indicating means and controlling a locking bar for dispensing a medal when certain of said targets are struck.

15 13. In a device of the character described the combination of means to fire balls; target members rigidly supported at one end toward which said balls may be fired; and means for variably indicating the targets hit.

14. In a device of the character described the combination of means to fire balls; spring target members rigidly supported at one end but free to move at the other end

and toward which said balls may be fired; and means for variably indicating the targets hit.

15. In a device of the character described 65 the combination of means to fire balls; a plurality of spring target members each rigidly supported at one end but free to move at the other end and toward which said balls may be fired; and means coating with the free 70 ends of said members for variably indicating visibly the targets hit.

16. In a device of the character described the combination of means to fire balls; a plurality of spring target members each rigidly 75 supported at one end but free to move at the other end and toward which said balls may be fired; and means released by the moving free ends of said members for variably indicating the targets hit.

17. In a device of the character described the combination of means for successively firing a number of balls; a plurality of targets toward which said balls may be fired; a spring support for each target provided with 85 an end adapted to move when said target is hit by a ball; slideable means for visibly indicating a hit target; and a connection between two of said indicating means cooperating with a dispensing means whereby both 90 targets associated with said indicating means must be hit to actuate said dispensing means.

18. In a device of the character described the combination of means for successively firing a number of balls; a plurality of targets toward which said balls may be fired; a spring support for each target provided with 95 an end adapted to move when said target is hit by a ball; slideable means controlled by said movable end for visibly indicating a 100 hit target; and a connection between two of said indicating means cooperating with a dispensing means whereby both targets associated with said indicating means must be hit to actuate said dispensing means.

19. In a device of the character described the combination of means for successively firing a number of balls; a plurality of targets toward which said balls may be fired; a spring support for each target provided with 110 an end adapted to move when said target is hit by a ball; slideable means for visibly indicating a hit target; and a slotted connection between two of said indicating means adapted to permit limited movement of either of 115 said means but full movement of both of said means when their associated targets are struck, said connection controlling a dispensing means.

In testimony whereof I affix my signature.

WALTER A. TRATSCH.
